UNITED STATES PATENT OFFICE.

SAMUEL N. RAPP, OF DETROIT, MICHIGAN, ASSIGNOR OF ONE-HALF TO
CHARLES GLOVER, OF NEW BRITAIN, CONNECTICUT.

COASTER-BRAKE AND HUB FOR BICYCLES.

SPECIFICATION forming part of Letters Patent No. 769,918, dated September 13, 1904.

Application filed March 31, 1903. Serial No. 150,420. (No model.)

To all whom it may concern:

Be it known that I, SAMUEL N. RAPP, a citizen of the United States, residing at Detroit, county of Wayne, State of Michigan, have invented a certain new and useful Improvement in Coaster-Brakes and Hubs for Bicycles; and I declare the following to be a full, clear, and exact description of the invention, such as will enable others skilled in the art to which it appertains to make and use the same, reference being had to the accompanying drawings, which form a part of this specification.

My invention has for its object certain new and useful improvements in a coaster-brake and hub for bicycles; and it consists of the combination of devices and appliances herein-after described and claimed, and illustrated in the accompanying drawings, in which—

Figure 1 is a view in side elevation of a hub fitted with my invention. Fig. 2 is a view in section on the line 2 2, Fig. 1. Fig. 3 is a view in section on the line 3 3, Fig. 2. Fig. 4 is a detail view of the sprocket-wheel, a portion of the same being in section, showing the bolt on the inside thereof. Fig. 5 is a view in section on the line 5 5, Fig. 4, looking to the right. Fig. 6 is a side elevation of the friction-shoe. Fig. 7 is a similar view from the opposite side showing the cams thereupon. Fig. 8 is an edge view of the double-faced cam. Fig. 9 is a view in elevation showing one face of the cam. Fig. 10 is a similar view showing the other face of the cam.

The purpose of my invention is to provide a coaster-brake and hub for bicycles of superior construction and utility wherein a positive lock is secured, whereby when coasting the locking device shifts through the sprocket into engagement with the brake cam or ratchet ready to set the brake, and whereby when pedaling ahead the locking device is shifted into engagement with the ratchet for propelling the wheel ahead.

My invention may be applied either to bicycles propelled by sprocket mechanism or by a chainless gear, as may be desired.

I carry out my invention as follows: In the

accompanying drawings, *a* represents the 50 axle, and *b* the shell of the hub. The axle passes through a cup *c* and a cone *d*, said axle and cup provided with a customary ball-bearing *e*, as shown. The axle is also provided toward its opposite end with a cone *f*, 55 having a threaded engagement therewith. The cup *c* has any suitable engagement with the adjacent end of the shell *b*. About the cone *f* is a detachable cup *g*, made detachable from the shell *b* in any suitable manner. Upon the 60 end of the axle adjacent to the cup *c* is secured a nut *h*. A sprocket-wheel *i* is shown loosely mounted upon the detachable cup *g*. The sprocket-wheel is shown formed with a hub *j*, projecting laterally from both faces thereof, 65 said hub being recessed in its inner periphery, as indicated at *k*, to receive a locking device or sliding bolt *l*, said bolt being arranged to move laterally in said recess from side to side. Said bolt is also arranged to rock in said recess in 70 case it should strike the high points of the ratchet-teeth when it is making its shift through the sprocket-wheel to engage the cam on either side of the sprocket-wheel. A non-revolvable cam is indicated at *m* on the outer side 75 of the sprocket-wheel, said cam provided with cam surfaces or teeth *n* on one side thereof and with teeth *o* on the opposite side thereof. A 80 brake-shoe *p* is provided, formed on one side thereof with cam surfaces or teeth *q* to engage the teeth *n* of the cam *m*. The shoe may be held stationary in any suitable manner, as by an arm *r*, constructed with flanges *s* to project astride a portion of the bicycle-frame, (indicated at *t*.) The opposite face of 85 the cam *m*, provided with teeth *o*, is engaged by the sliding bolt in the sprocket-wheel above described. The letter *u* indicates a ratchet-disk or toothed surface, the ratchet-teeth being indicated at *v* and made engageable by the 90 bolt in the sprocket-wheel to propel the wheel ahead. Adjacent to the brake-shoe *p* is a brake-disk *w*, against which the brake-shoe has frictional contact when forced outward. The brake-disk has a threaded engagement 95 upon the outer end of the adjustable cup *g*, as shown, and revolves with said cup. The inner surface of the brake-disk may be pro-

vided with any suitable facing, (not shown,) as of fiber or leather, for example. The sprocket-wheel is provided with a spring, (indicated at α ,) bearing upon the bolt l to keep 5 the bolt in proper position.

The operation of the device will now be understood and is as follows: In propelling the bicycle the bolt l engages the ratchet-disk to drive the hub. When it is desired to coast, the 10 feet of the rider being held still, the bolt shifts out of engagement with the ratchet-disk u , the bolt being in position to engage the adjacent teeth of the cam m , permitting the ratchet-disk to rotate without any movement 15 of the pedals. When it is desired to apply the brake by back pedaling, the bolt l engages the teeth of the cam m adjacent thereto forcing said cam into engagement with the 20 brake-shoe p , the shoe being thereby forced into frictional contact with the brake-disk w . If it is desired to apply my invention to a 25 chainless gear, a suitable gear could be substituted for the sprocket-wheel, said gear being provided with the sliding bolt l , said bolt being applicable to any desired driving mechanism. The teeth o on the cam m are formed with a short beveled surface, as shown. The 30 ratchet-teeth v of the disk u are also constructed with a beveled surface. The disk u is always rotating with the wheel. When the 35 rider ceases to propel the pedals, the disk goes ahead with the wheel, the bevel on the teeth thereby shifting the bolt through the opposite side of the sprocket-wheel ready to apply the brake. In back pedaling when the 40 rider starts to go ahead the sprocket-wheel is rotated, and the cam m being stationary the beveled surfaces of its teeth force the bolt toward and into engagement with the disk u .

40 What I claim as my invention is—

1. In a device of the character described in combination, an axle and its hub, driving mechanism therefor comprising a carrier provided with a laterally-movable positively-engaging locking device of greater width than the thickness of said carrier, means engageable by said locking device to propel said hub and brake mechanism engageable by said locking device.

45 2. In a device of the character described in combination, an axle and its hub, driving mechanism comprising a carrier provided with a laterally-movable positively-engaging locking device of greater width than the thickness of said carrier, means on one side of said driving mechanism engageable by said lock-

ing device to propel said hub and brake mechanism on the opposite side of said driving mechanism engageable by said locking device.

3. In a bicycle the combination of an axle, 60 a hub, a driving device loosely mounted upon the axle provided with a laterally-movable positively-engaging bolt, said device acting as a carrier for said bolt, said bolt being of greater width than the thickness of said carrying device, a toothed device, having a fixed engagement on one side of the driving device, a non-revoluble cam on the opposite side of the driving device engageable by said bolt, and a brake mechanism engageable by said 70 cam.

4. In a bicycle the combination of an axle, 75 a hub, a driving device provided with a hub recessed on its inner periphery, a laterally-movable positively-engaging bolt in said recess, a device to propel the hub engageable by said bolt, a cam on the opposite side of the driving device engageable by said bolt, and a brake mechanism engageable by said cam.

5. In a bicycle the combination of an axle, 80 a hub, a driving device provided with a hub recessed on its inner periphery, a rocking laterally-movable bolt in said recess, a device to 85 propel the hub engageable by said bolt, a cam on the opposite side of the driving device engageable by said bolt, and a brake mechanism engageable by said cam.

6. In a bicycle the combination of an axle, 90 a hub, a driving device on the axle provided with a sliding bolt, a device on one side of the driving device positively engageable by said bolt having cam-surfaces on both faces thereof, a brake-shoe adjacent to one of said cam-surfaces, a brake-disk adjacent to the brake-shoe, and a device on the other side of said 95 driving device positively engageable by said bolt to propel the hub.

7. In a bicycle the combination of an axle, 100 a hub, a driving device on the axle provided with a positively-engaging sliding bolt, a ratchet device having cam-surfaces or teeth on both faces thereof, a brake-shoe adjacent to one of said surfaces, a brake-disk adjacent to the brake-shoe, and a device on the other side of said driving device positively engageable by said bolt to propel the hub.

In testimony whereof I sign this specification in the presence of two witnesses.
